UNITED STATES PATENT OFFICE.

WILLIAM STEGER, OF COLUMBUS, OHIO.

AUTOMOBILE WINDOW CONSTRUCTION.

Application filed August 15, 1923. Serial No. 657,593.

To all whom it may concern:

Be it known that I, WILLIAM STEGER, a citizen of the United States, residing at Columbus, in the county of Franklin and 5 State of Ohio, have invented certain new and useful Improvements in Automobile Window Constructions, of which the following is a specification.

The present invention is directed to improvements in window constructions for the doors of automobiles of the closed type.

The primary object of the invention is to provide a device of this character so constructed that the window pane can be easily 15 slid to its open or closed position but at the same time will be held firmly to positively prevent rattling, the entrance of water, dust or other elements, the construction being durable, extremely simple and easy to install.

A further object of the invention is to provide a novel form of packing constructed and arranged so that the window pane will be firmly gripped contiguous to its edges, 25 but permitting the pane to move slightly in a lateral direction to absorb any shocks to which the pane may be subjected.

With these and other objects in view, as will appear as the description proceeds, the 30 invention consists in the novel features of construction, combinations of elements and arrangements of parts, and hereinafter to be fully described and pointed out in the appended claims.

35 In the accompanying drawing:

Figure 1 is a fragmentary side elevation of an automobile equipped with the device,

Figure 2 is an enlarged sectional view on line 2—2 of Figure 1, and

40 Figure 3 is an enlarged sectional view on line 3—3 of Figure 1.

The present embodiment of the invention is shown in connection with the door 1 of an automobile 2, but it will be of course understood that the construction may be used in 45 other connections if desired.

The door 1 as usual consists of an upper rail 3 and side rails 4 and lower members 5 which are so spaced as to provide a passageway 6 to accommodate the glass pane 7 so said pane can be slid downwardly. The construction thus far is customary and no claim is made therefor *per se*.

55 Suitably secured to the lower face of the rail 3 is a pair of moldings 8, said moldings being separated by a longitudinal space 9

for receiving the upper edge of the pane 7 when in its raised or closed position, there being a felt strip 10 secured in the base of the space for contact with the upper edge 60 of said pane. The confronting faces of the moldings 9 are provided with longitudinal channels 11, the purpose of which will appear later.

A spring plate 12 is secured at its lower 65 edge to each molding 8 by a series of screws 13, said plate having its free edge terminating in a channel member 14 adapted to move in the channel 11 as the plate yields due to the entrance and exit of the pane in the 70 space 9.

Engaged in each channel member 14 are felt strips 15 and in order to retain the strips securely in said member the upper plate thereof is provided with a plurality of 75 indentations 16 which are embedded in the strip and consequently hold the same firmly in place, these indentations being made in any suitable manner. It will be observed that the plates 12 are convergingly disposed, and since the same are formed from resilient sheet metal, preferably bronze, the felt strips will be compelled to tightly and yieldably engage the opposite sides of the pane 7, thereby preventing entrance of water 85 and dust. The side rails 4 are each provided with moldings 16' separated by a space 17 and also have their confronting faces formed with channels 18 which serve the same function as the channels 11 of the 90 moldings 8. Since the spring plates 19 and the mode of attachment of the felt strips 20 thereto in the channel members 21 are identical to the plates 12 a detail description thereof is not thought necessary. The 95 base of the space 17, like the base of the space 9 is provided with a felt strip 22 for contact with the side edges of the pane 7, it being of course understood that the sides of said panel are gripped between the felt 100 strips 20.

Upon the inner member 5 is secured a molding 23 having a channel 24 formed therein and in which the channel member 25 of the plate 26, similar to the plates 12 and 19, is accommodated to permit said plate to flex. A molding 27 is mounted upon the outer member 5 and is provided with a longitudinal seat 28. A protective metal sheathing 29 covers the molding 27 and has its 110 inner edge terminating in a tubular casing 30 which is supported upon the seat 28,

said casing being provided upon its inner side with a longitudinal slot 31. A section of normally round rubber tubing 32 is inserted endwise in the casing 30 so that a portion thereof will protrude through the slot 31 and forms in effect, a "squeegee" 33 for contact with the outer surface of the pane 7; this "squeegee" not only prevents entrance of water to the passageway 6 of the door, but also serves to absorb any shock in an outward direction upon the pane.

It will be of course understood that any well known type of mechanism may be employed for raising and lowering the pane 7.

From the foregoing description it will be apparent that the pane 7 will not only be held firmly in any of its adjusted positions, and owing to the presence of the felt strips upon opposite sides of the panel which are yieldably supported by the resilient plates, any shock imparted to the pane will be absorbed, thereby lessening the likelihood of the pane becoming broken.

What is claimed is:

1. In a device of the class described, the combination with upper laterally spaced moldings, side moldings also laterally spaced, resilient plates fixed to the confronting faces of the moldings and including diametrically opposed terminal channel members, felt strips secured in the channel members, a glass pane slidable in the spaces

between the moldings, said strips being yieldably engaged with the opposite sides of the glass pane, as and for the purpose set forth.

2. In a device of the class described, the combination with upper and lower moldings and side moldings, said moldings being laterally spaced, said upper and side moldings having resilient plates fixed to their confronting faces, said plates being provided with felt strips, one of the lower moldings having a resilient plate provided with a felt strip, the other lower molding having a casing carried thereby and provided with a longitudinal slot, a compressible tube located in the casing and having a portion protruding through said slot, and a glass pane movable in the spaces between the moldings and engaged with the respective felt strips and with the protruding portion of said tube.

3. A device of the class described comprising spaced moldings having channels in their confronting faces, resilient plates associated with the moldings and having terminal channel members movable in said channels, and packing strips fixed in the channel members for yieldably engaging a panel slidable between the molding.

In testimony whereof I affix my signature.

WILLIAM STEGER.
